H. C. EGERTON,
PROCESS OF MAKING BOOTS AND SHOES.
APPLICATION FILED FEB. 4, 1919.

1,352,738.

Patented Sept. 14, 1920.

By his Attorney Henry C Egerton
Harry L Duncan

UNITED STATES PATENT OFFICE.

HENRY C. EGERTON, OF RIDGEWOOD, NEW JERSEY.

PROCESS OF MAKING BOOTS AND SHOES.

Specification of Letters Patent. Patented Sept. 14, 1920.

1,352,738.

Application filed February 4, 1919. (Serial No. 274,937.

To all whom it may concern:

Be it known that I, HENRY C. EGERTON, a citizen of the United States, and resident of Ridgewood, Bergen county, New Jersey, have made a certain new and useful Invention Relating to Processes of Making Boots and Shoes, of which the following is a specification, taken in connection with the accompanying drawing, which forms part 10 of the same.

This invention relates particularly to processes of making footwear along the general lines described and claimed in my copending application Serial No. 233,000, filed May 7, 1918, by temporarily fastening the shoe upper having connecting portions of fabric or other elements or members, the coöperating connecting portions of these members carrying or being coated or impregnated with suitable phenolic condensation cementing material, such as bakelite, condensite or redmanol varnish or other suitable compositions and then all of the parts heat cured under pressure preferably together with a vulcanizable rubber sole element which may thus be securely connected to the other parts, if desired, and more or less molded or shaped and vulcanized at the same time. The shoe upper and coöperating stiffening members, such as toe box or counter elements having connecting portions of fabric carrying such cementing material may be advantageously fastened by being brought around a metal last and directly tacked or stitched together in any desired way to in-sole members and thus temporarily held in proper relative position so that they may by suitable mold elements comprising the last be pressed together and to rubber or other sole elements by a heat curing treatment sufficient to solidify or cure the phenolic condensation cementing stiffening material used in this connection.

The accompanying drawing shows in a somewhat diagrammatic way various illustrative forms of apparatus for carrying out this process, and

Figure 1 is a longitudinal vertical section through the coöperating mold elements which are shown in separated position for greater clearness.

Fig. 2 is a transverse section through the last and coöperating shoe elements which is shown in separated position for greater clearness; and

Fig. 3 is a similar transverse section through the corresponding portion of the shoe and mold elements.

The shoe upper 11 may be formed in whole or in part of canvas or other suitable fabric and may of course be preliminarily tailored or shaped in any suitable way so that it can be brought in place on the sectional last and molding element 5, 6 of any suitable construction which may have a junction portion 7 provided with suitable securing means, such as interlocking pins or fastening devices of any desired description not shown. The section 5 of this last may as indicated in Fig. 2 have a last recess 14 of such shape and depth as to more or less accommodate some of the sole members, such, for instance, as the in-sole member or layer 14 which may thus be definitely located. A more or less rounded edge bead or rib 8 may, if desired, be formed around this recess, although the shape of this edge portion of the last may of course be varied to suit different patterns or conditions, and if desired the last recess may have a more or less beveled portion 17 adjacent the edge rib or bead so as to avoid sharp corners in this part of the completed shoe. One or more such in-sole members 16 of canvas or other fabric carrying and preferably more or less impregnated with such phenolic condensation cementing material may be put in place in this last recess after being brought at moderate temperature to eliminate the varnish solvents and then preferably warmed somewhat to promote pliability. The shoe upper members may then be brought around the last in any suitable way and at least temporarily secured or fastened in this position as by the stitching or tacking in any desired way, the lasting stitching 21 being shown in Fig. 2 as serving this purpose and forcibly bringing the shoe upper 22 tightly around the last together with the alining or toe box fabric 23, the coöperating junction or connecting portions of these fabrics being similarly coated or impregnated with such phenolic condensation cementing material for best results. One or more intermediate in-sole members, such as 18, may be interposed between these fabrics and may be of canvas or other heavy strong fabric, or in some cases of paper or other fibrous material, such as cotton batting, paper pulp or suitable mixtures thereof, which may advance 100

105

110

tagenously be more or less coated or impregnated with such phenolic condensation cementing material, although, if desired, yieldable material, such as cork or similar in-sole 5 compositions may be used to a greater or less extent adjacent the inside of the shoe to cushion the wearer's foot, if desired. Additional layers of insoling material, such as 10, may be used and similarly coated or impregnated with such cementing material, which of course exerts a stiffening action on the completed sole in proportion to the number of layers used and the proportion of phenolic condensation cementing stiffening 15 material incorporated therewith. It is also desirable to have a connector layer, such as 20, provided with a rubberized coating 24 on its lower side as by spreading, frictioning or other coating methods so as to promote 25 union with the vulcanized rubber sole, the upper side or body of this connector fabric being coated with or carrying such cementing material to promote union with the other parts of the shoe. The rubber composition sole 12 which may, if desired, have an integral heel 13 of any desired shape and construction may be preliminarily contoured or molded roughly to shape and be assembled in the mold adjacent the connector fabric 30 so as to be securely and permanently united thereto and to the other sole elements during the heat pressure curing treatment described.

For this purpose an inclosing or collar mold element which may advantageously be 35 in sectional form may be used to inclose the shoe and molding last and this sectional mold collar may as indicated in Fig. 3 be formed of the sections 4, 25 having suitable portions 1, 2 as shown in Fig. 1 provided 40 with coöperating pins and holes, such as 29, which insure the accurate alinement of the parts as they are brought together. The bringing together and holding of these collar sections may be affected in any suitable 45 way as by forming holes, such as 9, in these mold sections to coöperate with the heavy locating and alining pins 10 in the mold bottom 3, so that when these parts are brought together the conical tops of these 50 locating pins first bring the collar sections of the mold into proper alinement and then definitely hold them as the mold is forced together in the vulcanizing and curing press. If desired also suitable closing latches may 55 be used to bring and hold together the upper or other parts of these mold collar elements and the latch 28 of heavy strong construction may be pivoted about the pin 31 in the collar section 25 so as to coöperate 60 with a corresponding pin 30 in the adjacent section 4 and have sufficient wedging action in connection therewith so that when the mold sections are forced together the press plunger or adjacent press plate forces this 65 latch down over its pin and strongly and

accurately brings these mold sections together. These collar molds are formed with a suitable mold face 27 preferably forming a somewhat narrow leakage rim for the rubber sole which is confined at its upper edge 70 portion by any suitable means such as a partition lip or edge 26 formed on this mold collar which is thus forced between the shoe upper and the rubber sole and adjacent parts to maintain proper separation at this point 75 as the rubber sole blank is under the vulcanizing heat and pressure forced into the different parts of the mold so as to more or less inclose the edge portions of the connector and adjacent stiffener members as 80 shown in Fig. 3. As indicated in Fig. 1, the bottom mold 3 is formed with a properly profiled sole portion 15 so that the rubber shoe sole is given the proper shape and thickness throughout its different parts and the 85 vulcanizable rubber composition comprising, if desired, suitable fibrous or inert strengthening and filling materials may thus be vulcanized and simultaneously united to the connector fabric while the phenolic condensation cementing material in this and other 90 fabric members is cured or solidified so as to thoroughly and permanently unite all of these parts. This curing vulcanizing heat may be supplied to the mold elements in any 95 suitable way as by external heating or steam plates or by electric or steam heating elements in the mold sections themselves by which the curing vulcanizing heat of 250° to 320° F. more or less is exerted on the shoe 100 elements for a quarter or half an hour more or less according to the rubber and cementing compositions employed.

In some cases it is desirable to first last up the shoe upper and the coöperating insole fabric or other members, such as 16, 18, and then after assembling the collar mold sections and the mold bottom with the rubber sole 12 and the connector and other elements, such as 19, 20, in connection therewith, the molding last and shoe upper may be inserted from the top through the enlarged cavity 35 in the mold collar so as to be brought into engagement with the other elements of the shoe sole, and as the press 115 closes it acts on the mold last within the shoe and forces the coöperating junction or connecting portions of these shoe sole and upper elements strongly together under hydraulic pressure, for instance, so that the 120 proper engagement of these fabric elements is insured, the edge bead or rib 8 of the last 5 more or less stretching the shoe upper members and forcing them down into shape and effective uniting engagement with the 125 fabric or other sole elements below so that the phenolic condensation cementing material can certainly and effectively unite the connecting portions and obviate in most cases the necessity of further stitching or 130

securing these parts of the shoe together. This action furthermore effectively forces the shoe upper down against the partition lip or edge 26 so as to prevent upward leakage at this point during the subsequent heat curing operation which sufficiently softens the vulcanizable rubber sole composition so that it is forced more or less up around the connector 20 and the adjacent members 5 which are in most cases somewhat distorted or bent or carried upward by this action of the rubber. It is of course understood that the rubber sole blank used contains sufficient material so that after forcing all of the 10 parts together as above indicated the excess rubber is forced out of the mold past the relatively narrow mold faces 27, for instance, and the resulting fins or leakage portions may be ground or trimmed off in 15 finishing the vulcanized united shoe. In some cases the fabric or fibrous sole elements may be permanently united without simultaneously uniting them to a rubber sole and this may be conveniently accomplished, for example, by having the canvas or other fabric layers 19, 20 extend out to the edges of the mold recess below the partition lip 26 and both of these fabric layers may in that case be more thoroughly impregnated or filled with phenolic condensation cementing material with or without such rubberized coating or facing as previously described. The rest of the recess may be filled by an upward projection on the 20 mold bottom 3 or by inserting a separate sole shaped metallic blank for this purpose, so that when the last mold and shoe elements assembled thereon are forced down under the heavy pressure into the mold collar the heat of the mold effects the curing of this phenolic condensation cementing material in the coöperating junction or connecting portions of these shoe elements so as to effect their secure and permanent 25 union and provide a projecting fabric welt or edge portion around the shoe sole which may be stitched or otherwise attached to a rubber or other shoe sole of any desired composition or character.

50 This invention has been disclosed in connection with a number of illustrative embodiments, forms, proportions, elements, parts, shapes, materials, compositions, conditions and methods of preparation, production and use, to the details of which disclosure the invention is not of course to be limited, since what is claimed as new and what is desired to be secured by Letters Patent is set forth in the appended claims:

60 1. The process of making shoes which comprises assembling on a molding last and temporarily connecting an upper and insole elements having fabric connecting portions carrying phenolic condensation cementing material, inserting said last and

assembled elements into the cavity in a sectional mold provided with an inwardly projecting partition lip to coöperate with the edge portions of said mold last to force said connecting portions into coöperation with a vulcanizable rubber sole and fabric connector member beneath said partition and holding said mold and shoe elements together during a heat curing treatment to vulcanize said rubber sole and cure said phenolic condensation cementing material and unite the connecting portions of said shoe elements.

2. The process of making shoes which comprises assembling on a molding last and temporarily connecting an upper and insole elements having fabric connecting portions carrying phenolic condensation cementing material, inserting said last and assembled elements into a sectional mold provided with an inwardly projecting partition member to coöperate with the edge portions of said mold last to force said connecting portions into coöperation with a vulcanizable rubber sole and fabric connector member beneath said partition member and holding said mold and shoe elements together during a heat curing treatment to vulcanize said rubber sole and cure said phenolic condensation cementing material and unite the connecting portions of said shoe elements.

3. The process of making shoes which comprises assembling on a molding last an upper and sole elements having fabric connecting portions carrying phenolic condensation cementing material, inserting said last and assembled elements into a mold provided with an inwardly projecting partition member to coöperate with the edge portions of said mold last to force said connecting portions into coöperation with a vulcanizable rubber sole beneath said partition member and holding said mold and shoe elements together during a heat curing treatment to vulcanize said rubber sole and cure said phenolic condensation cementing material and unite the connecting portions of said shoe elements.

4. The process of making shoes which comprises assembling on a molding last an upper and sole elements having fabric connecting portions carrying phenolic condensation cementing material, forcing said last and assembled elements into coöperation with an inwardly projecting partition member arranged to coöperate with the edge portions of said mold last and forcing the inner portions of a vulcanizable rubber sole and fabric connector member beneath said partition member into engagement with said sole elements and holding said shoe elements together during a heat curing treatment to vulcanize said rubber sole and cure said phenolic condensation cementing material.

- and unite the connecting portions of said shoe elements.
5. The process of making shoes which comprises assembling on a molding last an upper and sole elements having fibrous connecting portions carrying phenolic condensation cementing material, forcing said last and assembled elements into coöperation with an inwardly projecting partition member 10 arranged to coöperate with the edge portions of said mold last and forcing the inner portions of a vulcanizable rubber sole beneath said partition member into engagement with said sole elements and holding 15 said shoe elements together during a heat curing treatment to vulcanize said rubber sole and cure said phenolic condensation cementing material and unite the connecting portions of said shoe elements.
- 20 6. The process of making shoes which comprises assembling on a molding last an upper and sole elements having fibrous connecting portions carrying phenolic condensation cementing material, forcing said last 25 and assembled elements into coöperation with a partition member and with a vulcanizable rubber sole adjacent said partition member into engagement with said sole elements and holding said shoe elements together during a heat curing treatment to 30 vulcanize said rubber sole and cure said phenolic condensation cementing material and unite the connecting portions of said shoe elements.
- 35 7. The process of making shoe elements which comprises assembling on a molding last and temporarily connecting an upper and in-sole elements having fabric connecting portions carrying phenolic condensation 40 cementing material, inserting said last and assembled elements in a sectional mold provided with an inwardly projecting partition to coöperate with the edge portions of said mold last and be forced into engagement 45 with sole elements comprising a fabric connector member beneath said partition and holding together and heating said mold and shoe elements to cure said phenolic condensation cementing material and permanently 50 and strongly unite the connecting portions of said shoe elements.
8. The process of making shoe elements which comprises assembling on a molding last an upper and insole elements having 55 fabric connecting portions carrying phenolic condensation cementing material inserting said last and assembled elements in a sectional mold provided with an inwardly projecting partition to coöperate with the 60 edge portions of said mold last and be forced into engagement with sole elements comprising fabric connector material beneath said partition and holding together and heating said mold and shoe elements to 65 cure said phenolic condensation cementing
- material and permanently and strongly unite the connecting portions of said shoe elements.
9. The process of making shoe elements which comprises assembling on a molding last an upper and sole elements having 70 fibrous connecting portions carrying phenolic condensation cementing material, inserting said last and assembled elements in a sectional mold into engagement with an inwardly projecting partition to coöperate 75 with the edge portions of said mold last and be forced into engagement with sole elements comprising fibrous connector material adjacent said partition and holding together and heating said mold and shoe 80 elements to cure said phenolic condensation cementing material and permanently and strongly unite the connecting portions of said shoe elements.
10. The shoe making process comprising 85 assembling an upper and shoe stiffening means including an insole of fabric carrying phenolic condensation cementing material, and an additional fabric sole element coated on its contacting surface with phenolic condensation cementing material and bringing a rubber sole into contact with said sole element and compressing and heating said parts to simultaneously cure the phenolic condensation material and vulcanize 90 the rubber and permanently unite them.
11. The shoe making process comprising assembling an upper, a sole stiffening member formed of fabric carrying phenolic condensation cementing material and a rubber 100 element, and compressing and heating such elements to simultaneously cure, vulcanize and permanently unite them.
12. The shoe making process comprising assembling an upper, a sole stiffening member comprising fibrous material carrying phenolic condensation cementing material and a rubber element, and compressing and heating such elements to cure, vulcanize and 105 unite them.
13. The shoe making process comprising assembling an upper element, a sole member comprising fibrous material carrying phenolic condensation cementing material and a rubber element, and heating such elements to unite them.
14. The shoe making process comprising assembling and preliminarily connecting upper, insole and shoe stiffening members having coöperating portions formed of fabric 110 impregnated with phenolic condensation cementing material, compressing therewith a vulcanized rubber composition sole and heating the coöperating parts of said elements to simultaneously cure the phenolic condensation material in such shoe elements and vulcanize the rubber and permanently 115 unite such elements.
15. The shoe making process comprising assembling and preliminarily connecting 120
- 125
- 130

an upper, an insole and a shoe stiffening member having coöperating portions formed of fabric impregnated with phenolic condensation cementing material, and in compressing and heating said portions to simultaneously cure and solidify the phenolic condensation material in such shoe elements and permanently unite them.

16. The shoe making process comprising assembling an upper and a shoe member having coöperating portions formed of fibrous material carrying phenolic condensation cementing material, and heating said portions to cure the phenolic condensation material in such shoe elements and unite them.

17. The shoe making process comprising assembling a rubber sole, an upper and an interposed fabric sole element, carrying phenolic condensation cementing material

and holding together and heating said parts to simultaneously cure, and unite said elements.

18. The process of making footwear which comprises assembling an upper element and a fabric sole element carrying phenolic condensation cementing material in their coöperating portions, and a vulcanizable rubber sole, and holding together and heating said elements to simultaneously cure, vulcanize and unite them.

19. The process of making footwear which comprises assembling an upper element and a fibrous sole element carrying phenolic condensation cementing material in their coöperating portions, and a vulcanizable rubber sole element, and heating said elements to cure and unite them.

HENRY C. EGERTON.
